FLEXIBLE ALIGNMENT DRIVE

John P. Kolb, New York, N. Y., assignor to General American Transportation Corporation, Chicago, Ill., a corporation of New York

Application April 2, 1947, Serial No. 739,010

7 Claims. (Cl. 74—705)

1

This invention relates to flexible drive couplings and particularly to flexible drive couplings which permit the driving, with a minimum loss of power and with a minimum of lateral thrust, of a driven part, the axis of which is slightly eccentric to or even slightly inclined to the driving member. More particularly the invention relates to driving mechanism for use in driving the rake or scraper carrying arms of sedimentation apparatus of the type commonly known as thickeners or clarifiers in which the arms which effect the gradual movement of the solids toward the central discharge part of the thickener are carried by a drum or cage arranged to have both rotary and axial movements imparted thereto by mechanism located at the center of the apparatus.

In driving the drum on which the blade or rake-carrying arms are mounted in sedimentation apparatus of the type shown in the co-pending application of Roman Chelminski et al., Serial No. 588,278, filed April 14, 1945, provision must be made in the driving connections between the reduction gearing and the arm-carrying drum for axial movement of the drum both to relieve overloads and to return to normal position after the relief of the overload has been effected, without interrupting the rotation of the arms. Provision must also be made in the connections for slight eccentricities of the drum axis in respect to the axis of the driving gear.

One of the objects of the present invention, therefore, is to provide a flexible drive coupling between the drum and the reduction gearing from the source of power which is particularly adaptable for use with sedimentation apparatus of the general type above referred to and which will permit continued driving without substantial loss of power or substantial lateral thrusts on the drum or driving gear, even when the axis of the driving gear and the axis of the drum are slightly eccentric or even when they are at slight angles to each other.

Another object of the invention is the provision of rolling contact between the drum and the driving gear, in driving mechanism of the type above referred to, such that, when axial relative movement of the drum and driving gear take place, particularly when this movement takes place under extremely heavy torque loads, there will be no excessive end thrusts on either the drum or the driving gear.

Another object of the invention is to insure adequate lubrication of the parts of the flexible drive coupling through which power is transmitted from the driving source to the driven parts.

2

To this end an important feature of the invention is the arrangement of the relatively movable parts of the flexible drive coupling in such manner that they lie between horizontal planes, whereby the engaging parts of the elements of the coupling may have their engaging surfaces immersed in oil baths maintained in recesses in the upper faces of the lower elements.

Another important feature of the invention is 10 the provision of a flexible drive coupling which is so constructed that the driving power may be transmitted to one of the relatively movable parts of the coupling through an internal annular gear, this feature of the construction also permitting 15 the location of a substantial part of the reduction gearing within the flexible drive coupling.

Still another important feature of the invention is the provision of a flexible drive coupling, operating on the general principles of the Oldham 20 coupling, in which all three elements of the coupling are of ring form so that the coupling as a whole may surround the reduction gearing and other elements of the transmission through which power is transmitted from a source of power to 25 the part or parts to be driven.

Other objects, important features and advantages of the invention, to which reference has not specifically been made hereinabove, will appear hereinafter when the following description and 30 claims are considered in connection with the accompanying drawings, in which—

Figure 1 is a side elevation partly broken away and partly in section, of a drum driving mechanism embodying the present invention and incorporated in a sedimentation apparatus or thickener 35 such as more fully shown and described in the co-pending application of Roman Chelminski et al., Serial No. 588,278, filed April 14, 1945;

Figure 2 is a view partly in section and partly 40 in plan taken on the line 2—2 of Figure 1;

Figure 3 is a view in enlarged axial section of the drive mechanism including the flexible drive coupling shown centrally in Figure 1;

Figure 4 is a cross sectional view taken on the 45 line 4—4 of Figure 3;

Figure 5 is an enlarged detail of a portion of the structure shown in Figure 4, and

Figure 6 is a vertical section of the portion 50 shown in Figure 5 taken on the line 6—6 of Figure 4.

As more fully set forth in the co-pending application of Roman Chelminski et al. hereinabove identified, the invention is shown as embodied in and as particularly adaptable to the mechanism 55 for transmitting driving power from a source of

power, such as electric motor 26, to a drum 52a on which are mounted the rake or scraper-blade carrying arms of a sedimentation apparatus or thickener such as disclosed in said co-pending application. Since such sedimentation apparatus is usually of relatively large size, for example the tank in which the arms turn may be 150 feet in diameter, it will be seen that the torque, required to move the arms through the tank and effect by such movement the gradual movement of the sediment toward the central discharge part of the tank, will be comparatively great. It will also be seen that leverages from torque reactions on these relatively long arms will be comparatively great, and that both the said leverages about the axis and those occurring from incidental obstructions, which may tend to effect a slight tilting of the axis of the drum, will be great.

As here shown and as more fully described in the co-pending application, the reduction gearing and the flexible drive coupling are mounted upon the upper end of a hollow pier 14 in which a frame 62, mounted upon a hydraulic jack or elevator, located in the bottom of said pier and not herein specifically shown but shown fully in said copending application, is vertically movable by said jack or elevator, the frame 62 including horizontal I-beams 63 which extend through slots 64 in the pier 14. A track 60 supported on the I-beams 63 outside the pier 14 serves to support the drum 52a for rotation about its axis and about the central pier 14. As shown, stub shafts 54 and 55 project from the inner circumference of the drum 52a and carry rollers 58 and 59, the upper flanged rollers 58 travelling on the track 60 and the lower rollers 59 engaging beneath the flange 61 for the purpose of preventing the scraper assembly from lifting away from the track 60 or, vice versa, to prevent the track 60 from dropping away from the roller 58 on the lowering of the elevator.

As more fully set forth in my co-pending application, Serial No. 739,009, filed herewith, in order to insure a substantially equal division of the load between two reducing gear trains, 154—28a—30a—38a, the motor shaft 158 is connected to these gears through a differential comprising a central spider 160 keyed on shaft 161 and having rotatably secured thereon a plurality of bevel pinions 162. Bevel gears 163 and 164 rotatably mounted on the shaft 161, which is positively secured to the shaft 158, intermesh with the bevel pinions 162. A drive gear 166 connected to the upper bevel gear 163 meshes with the intermediate gear 156 to drive the gear train on the right hand side of Figure 3. The lower gear 164 of the differential is keyed directly to a drive gear 168 which drives the gear 155 and through it the gear train on the left hand side of Figure 3.

The last pinion 38a of each of the aforementioned two gear trains meshes with an internal ring gear 42a. The ring of which this gear forms a part constitutes one of the three relatively movable elements of the flexible drive coupling now to be described. This coupling comprises, besides the ring 42a, two other rings 176 and 152, preferably of substantially the same overall diameter as the ring 42a and normally concentric therewith. The lower ring 42a, which has the aforementioned ring gear on its inner face, carries on its upper side a roller 180 mounted on a short shaft or post 181 and a rocker arm 182 mounted on another short shaft or post 184, there being a roller 180 and rocker arm 182 at opposite ends of one diameter of the ring 42a. An arm

or lug 186 projecting from the lower side of the intermediate ring 176 is engaged between each rocker 182 and the associated roller 180. These lugs 186 are located at diametrically opposite points on the ring 176 and preferably have their roller and rocker arm engaging faces substantially parallel to the said diameter of the ring 176 for a purpose hereinafter set forth.

Each roller 180 and its associated rocker 182 are received in a recess 188 formed in the upper face of the ring gear 42a. Other recesses 190 are formed at angularly spaced positions about the circumference of the ring into which extend bearing posts 192 projecting downwardly from the intermediate ring 176, each of these posts being of a diameter somewhat less than the width of the recess 188 into which it extends in order to permit a limited relative horizontal movement of the two rings 176 and 42a. Similarly it will be seen that the lugs 186 each has its greater transverse dimension somewhat less than the width of the recess 188 to permit relative movement of the rings 176 and 42a in directions coinciding with the diameter of the ring 176 on which the two lugs 186 are located. Each of the recesses 188 and 190 may be filled with oil so that the bearing surfaces, that is the engaging surfaces of the various relatively movable parts, may be adequately lubricated over long periods of time.

The intermediate ring 176, shown in section in Figure 3, a fragment thereof being also shown in plan at the left hand side of Figure 4, has, as above pointed out, formed on the bottom thereof the bearing posts 192 and the driving lugs 186. On its top face the ring 176 has formed, either integrally therewith or fixedly attached thereto, posts 198 and 199, corresponding to the posts 181 and 184 of the ring 42a and similarly provided with rollers 180 and rocker arms 182, at positions 90° removed from the lugs 186. Between these rollers 180 and rocker arms 182 on the upper face of the ring 176 are received driving lugs 200, similar to the lugs 186 on the ring 176 but projecting downwardly from the under face or bottom of the uppermost or drum-driving ring 152.

Recesses 202 and 204 are provided in the upper face of the intermediate ring 176, these recesses corresponding to the recesses 188 and 190 in the upper face of the ring 42a. These recesses serve the same purpose of maintaining a bath of lubricant for the engaging relatively movable parts of the uppermost ring 152 and the intermediate ring 176. Thrust bearing posts 206, similar to the thrust bearing posts 192 on the under side of ring 176, extend from the under side of the ring 152 into the recesses 204 on the upper face of the ring 176 and rest on the bottoms of these recesses 204, thus providing vertical thrust bearings similar to those between the rings 176 and 42a, where the posts 192, projecting from the under side of ring 176, engage the bottoms of the recesses 190. Bearing plates 193 and 205 of bronze or other bearing metal, suitably polished, may be fitted in the bottoms of the recesses 190 and 204, respectively, to provide smooth, level bearing surfaces for the lateral sliding movements of posts 192 and 206. As above suggested, the recesses 202 and 204 in the upper face of the intermediate ring 176 and the recesses 188 and 190 in the upper face of the ring 42a may be filled with oil so that all the engaging relatively movable parts of the respective rings may be constantly bathed in oil and thus adequately lubricated for comparatively frictionless relative movement over long periods of time.

An apron 208, depending from ring 152, and felt gaskets at the periphery of frame 22a on the lower periphery of ring 42a and on the upper periphery of ring 152 complete the closure of the housing for the flexible drive coupling against dust, spray, etc.

In the operation of this drive the torque applied from the drive shaft 158 is, as above suggested, divided equally by the differential on shaft 161 and applied through two gear trains to diametrically opposite points of the gear ring 42a. The driving torque is transmitted through the posts or shafts 181 and 184 and the rollers 180 and rocker arms 182 to the lugs 186 located at diametrically opposite points on the intermediate ring 176, thus effecting rotation of the intermediate ring 176 and in turn transmitting torque through the posts 198 and 199 and the rocker arms 182 and rollers 180 on the upper side of the ring 176 to the lugs 200 projecting from diametrically opposite points on the under side of the uppermost ring 152 and effecting rotation of this ring.

The driving connections between the flexible drive coupling thus far described and the drum 52a comprise an upward extension of the drum above its supporting rollers 58, in which upward extension are formed vertical slots provided with bearing rails 48a, U-shaped in section, on which anti-friction rollers 150 carried on stub shafts 151 travel. The stub shafts 151 are fixed upon the uppermost ring 152 of the above-described flexible drive coupling. From the foregoing description it will be seen, therefore, that the torque transmitted from the ring gear 42a through the intermediate coupling ring 176 to the uppermost ring 152 of the flexible drive coupling is in turn transmitted through the stub shafts 151 and the rollers 150 to the drum 52a and thus to the rake or scraper blade carrying arms, not shown, which are mounted upon the drum 52a.

From the drawings it will be noted that the posts 181 and 199 on which the rollers 180 of the respective rings 42a and 176 are mounted are positioned to hold the lugs 186 and 200, respectively projecting from the under sides of the rings 176 and 152 against the rockers 182 without play, so as to avoid overrunning and impact which might overload the driving connections. It will further be observed that, as above pointed out, the lugs 186 lie at opposite ends of one diameter of the ring 176 and the lugs 200 at the opposite ends of a diameter of said ring 176 perpendicular thereto, when the rings are concentric, and that the rockers 182 and the rollers 180 are designed to allow movements of these lugs along but not away from their respective diameters. Thus any eccentricity between the drum 52a and the fixed path of the ring gear 42a is freely accommodated in the same manner in which eccentricity between the axes of driving and driven shafts may be accommodated by the familiar Oldham couplings, and without objectionable stresses on the parts concerned. Since any such eccentricity, so long as it may be present, will require constant readjustment of the relations of the three rings 42a, 176 and 152 during rotation, it is important to have good and adequately lubricated thrust bearing surfaces between the rings. This is provided for, as hereinabove pointed out, by providing the wells 190 and 204, for lubricating oil, into which project the bearing posts 192 and 206 and which have in their bottoms polished bearing plates 193 and 205.

As shown in Figure 4, each of the rockers 182 is

provided with a spring 210 secured to a lug 212 on the rocker. The action of the spring 210 is restricted between pins 214, also secured on the rocker, and pins 216 which are secured respectively in lug 186 and lug 200 above each rocker arm on the next ring above. Thus the spring 210 can always restore the rocker 182 to a mid-position in respect to the mid-point of the driving lug 186 or 200 whenever it is relieved of load. The spring thus resists any tendency of the rocker arm to work over against one side or the other of the ring recess in which it is located, and since the spring is held between the pins 216 of lug 186 it also tends to position the lug 186 centrally in the recess 188, thereby tending to urge the rings toward concentric positions. The curved side walls of recess 188 act as abutments to limit radial movement of lug 186 and thus limit relative transverse movement of the rings.

20 It should be noted that the section shown in Figure 4 is taken at a higher level at the left than at the right of this figure, as indicated by 4-4 of Figure 3, and that the section of the rings 42a, 176 and 152 and of the drum 52a is taken at the 25 upper branch of the line 3-3 on Figure 4, whereas the other parts shown on Figure 3 are sectional along the lower branch of the line 3-3 on Figure 4.

It will also be noted that, for greater clarity of showing, the section at the upper portion of Figure 4 is taken at a somewhat higher level than the section at the lower portion of this figure, the former passing through that portion of lug 186 which carries the pins 216, whereas at the bottom of Figure 4 the pins 216 (as also indicated by line 5-5 on Figure 6) are shown in section below the level of the part in which they are anchored.

What is claimed as new is:

What is claimed as new is:

40 1. An annular drive coupling adapted to accommodate substantial eccentricity between a driving member and a driven member, which comprises terminal rings, one connected to said driving member and the other connected to said driven member, and an intermediate ring; one 45 of said terminal rings and the intermediate ring each having flat-bottom wells distributed about its circumference in one side thereof and paired pivoted dogs with rotatable faces lying close to opposite sides, respectively, of a single diameter 50 on each ring, those on each ring lying along a diameter perpendicular to that on the other ring; the other of said terminal rings and the intermediate ring having bearing lugs projecting into said wells with substantial clearance to accommodate, but to limit, lateral movement between said rings, and having driving lugs with faces lying, respectively, close to said diameter on each ring and projecting between said paired pivoted dogs.

60 2. An annular drive coupling adapted to accommodate substantial eccentricity between a driving member and a driven member which comprises terminal rings, one connected to said driving member and the other connected to said driven member, and an intermediate ring; each of said terminal rings and the intermediate ring having a plurality of cooperating abutments at a plurality of positions circumferentially distributed about each ring, the abutments on the facing sides of adjacent rings being at substantially the same circumferential position and those on one of said rings having radially spaced portions adapted to engage that on the facing ring with clearance to accommodate, but to limit, transverse relative movement, and interengaging dogs

on said facing rings having their engaging faces lying substantially on an axial plane, whereby to accommodate transverse relative movement while transmitting torque, those on one terminal ring and the intermediate ring lying on one axial plane and those on the other terminal ring and the intermediate ring lying on the perpendicular axial plane.

3. In an apparatus of the class described, the combination with a rotary carriage and a vertically movable support on which the carriage is rotatable about a fixed axis, of a motor and a torque-transmission connection between the motor and the carriage, said torque-transmission connection comprising an Oldham coupling including a driving member, a driven member and an intermediate member, each of said members being transversely slideable and rotationally engaged with respect to its adjacent member, a vertical track element and cooperating rotatably mounted roller element at each of a plurality of points spaced around the periphery of said carriage and coupling, one of said elements being secured to said carriage and the other element being secured to the driven member of said coupling, whereby said carriage is rotatable by said driven member and is vertically movable with respect to said driven member during rotation.

4. The combination as defined in claim 3 in which the carriage comprises a central drum slotted at a plurality of places parallel to its rotational axis, each slot being of a width adapted to receive one of the roller elements and the edges of said slots forming said track elements.

5. The combination as defined in claim 3 in which the torque-transmission connection comprises, in addition to the Oldham coupling a reduction gear train interconnecting the motor and the driving member of said coupling.

6. The combination as defined in claim 5 in which the Oldham coupling is annular and its driving member is an internal ring gear coaxial with said fixed axis of the carriage, and the motor is mounted with its drive shaft also coaxial with said fixed axis and tandem gear reduction trains interconnect said motor shaft and ring gear.

7. The combination as defined in claim 4 in which the drum is upright and rotatable about a vertical axis; the Oldham coupling is annular with a reduction gear train in the central space within the coupling; the driving member of said

coupling is an internal ring gear; and annular bearing on said support rotatably mounts the ring gear thereon to rotate on a fixed axis; the said driving member and intermediate member each have spaced flat-bottom wells filled with lubricant in its upper face; the intermediate member and the driven member of said coupling, respectively, have bearing lugs projecting from the bottom face of each and resting in said wells of the intermediate and driving members respectively, with clearance from the sides thereof to accommodate, but to limit, movement relative to said wells; each of said intermediate and driven members have driving lugs projecting from the bottom thereof with opposite faces of the lugs on each member lying close to a single diameter thereof for driving engagement with the driven and intermediate members respectively; and the driving member and intermediate member, respectively, of said coupling have secured on their upper sides paired pivoted dogs engaging opposite radial faces of said driving lugs whereby to transmit driving torque while permitting substantially free transverse movements within the limits prescribed by said wells, said paired pivoted dogs on the intermediate member of the coupling being on a diameter perpendicular to the diameter of the driving lugs on the same driven member.
